CLAIM

The ornamental design for a camouflage pattern for sheet goods, as shown and described.

DESCRIPTION

FIG. 1 is a plan view of a camouflage pattern for sheet goods showing a first embodiment of my design; and, FIG. 2 is a plan view of a second embodiment thereof. The broken line border is indicative of indeterminate size and shape and is no part of the claimed Design. It is to be understood that coloration and color combinations of the pattern as well as scale of the repeat unit may be varied. The varying patterns of grey tones, dots, and solid black are understood to represent contrasting colors.
